ATTORNEY

UNITED STATES PATENT OFFICE.

JOSEPH BARRY AND WILLIAM J. THOMÉE, OF HEWLETT, NEW YORK.

SPRING-HANGER.

1,263,637.

Specification of Letters Patent. Patented Apr. 23, 1918.

Application filed December 1, 1916. Serial No. 134,457.

To all whom it may concern:

Be it known that we, JOSEPH BARRY, a British subject, and WILLIAM J. THOMÉE, a German subject, both residing at Hewlett, 5 Long Island, in the county of Nassau and State of New York, have invented certain new and useful Improvements in Spring-Hangers, of which the following is a specification.

10 The invention relates to spring hangers and more particularly to a spring hanger for use in connection with automobiles and similar vehicles.

One of the main objects of the invention 15 is to provide a hanger for an automobile the width of which may be quickly and easily adjusted so as to take up all play, thus preventing rattling and unnecessary wear of the spring.

20 A further object is to provide a hanger of the character stated of simple construction and operation which may be produced at relatively low cost.

25 Further objects will appear from the detailed description.

In the drawings:

Figure 1 is a side view of the hanger as applied,

30 Fig. 2 is a transverse vertical sectional view taken substantially on line 2—2 of Fig. 3, and

Fig. 3 is a section taken on line 3—3 of Fig. 2.

In the common form of spring hanger 35 now in use, the end plates of the hanger are integrally connected by a central web member, being substantially H shape, the central web being provided to prevent lateral play of the end plates and the consequent wear and tear on the securing bolts.

40 As a result of this construction, when a spring wears so as to have slight lateral play, it is necessary to insert a suitable washer between the side of the spring and the hanger side plates to take up this wear and prevent rattling and unnecessary wear of the spring. In practice this is a very difficult job and needs considerable time and work. In carrying my invention into effect I avoid these objections by replacing 45 the central web member of the common form of hanger by a threaded element which may be utilized for adjusting the plates of the hanger toward and away from each other, thus rendering it possible to take up any play of the spring.

The side plates 1 and 1^a of the hanger are each provided, at each end, with an integral enlargement 2. These enlargements of the plates are centrally apertured to receive the upper securing bolt 3 and the lower bolt 4. Bolt 3 is passed through the side frame member 5 in the usual manner, and the bolt 4 is passed through the eye 6 of the spring 7. Bolt 3 is provided, at its outer end, with a nipple 8 secured thereon and interiorly threaded to receive the stem 9 of an oil cup 10, the bolt 4 being provided with a similar nipple 10^a which receives the stem 11 of an oil cup 12. Each of the bolts is provided with an inwardly extending bore 13 which communicates at its outer end with the interior of the nipple and at its inner end with an oil duct 14. By this means, the oil is supplied from the oil cups to the bearing surfaces between the bolts and the frame member and spring.

Midway between the bolts 3 and 4, is mounted an adjusting bolt 15. This bolt is provided at one end, with a reduced portion 16 which is inserted through the side plate 1 of the hanger and is spread or headed as at 17. By this means the bolt 15 is secured against axial movement, in either direction relatively to the inner plate of the hanger. The outer end portion of bolt 15 is threaded as at 18. A nut 19 is threaded on the bolt 15 inside of the outer plate 1^a, and a similar nut 20 is threaded on the bolt outside of plate 1^a, the bolt being passed through an aperture 20 through plate 1^a in alignment with the aperture in plate 1 through which the reduced portion 16 of the bolt 15 is secured.

When it is desired to draw the side plates 1 and 1^a of the hanger toward each other so as to take up wear of the spring, it is only necessary to turn the nut 19 inward on bolt 15 and to thread the nut 20 on to the bolt thus forcing the two plates toward each other. When the desired adjustment has been effected, the nut 19 is again moved into engagement with the inner face of plate 1^a, the nuts 19 and 20 coacting to prevent movement of plate 1^a in either direction. If it is desired to widen the hanger by moving the plates 1 and 1^a away from each other, this may be accomplished by first removing the nuts 21 from the securing bolts 3 and 4, and then turning nut 20 outward on bolt 16 out of engagement with plate 1^a, after which this plate may be forced away from plate 1 by means of the nut 19. Either one of these

adjustments may be quickly and easily effected, and all play due to wearing of the spring or the side bar of the frame may be quickly and easily taken up without the necessity of inserting spacing washers or similar elements into the hanger. In addition, the adjusting bolt 15 also serves to effectually prevent lateral play of the side plates 1 and 1^a, such as would tend to cause unnecessary wear or friction on the securing bolts 3 and 4.

There may be slight changes made in the construction and arrangement of the different parts of our invention without departing from the field and scope of the same, and we intend to include all such changes, as fall within the scope of the appended claims, in this application in which a preferred form only of our invention is disclosed.

20 What we claim is:

1. In spring hangers, the combination of two spaced plates, and means for adjusting said plates toward and from each other.

2. In hangers, the combination of two spaced plates, and means for moving said plates toward and from each other and for

securing the plates in adjusted spaced relation.

3. In hangers, the combination of two spaced plates, an adjusting bolt secured in one of said plates intermediate the ends thereof and passed through the other plate intermediate its ends, a nut threaded on said bolt adjacent the inner face of the last mentioned plate, and a nut threaded on the said adjusting bolt outside of the said last mentioned plate.

4. In hangers, the combination of two spaced plates, an adjusting member secured in one of said plates and extended through the opposite plate, and means mounted upon said adjusting member for engagement with opposite faces of the second mentioned plate to hold the same in adjusted spaced relation with the first mentioned plate.

In testimony whereof we affix our signatures in presence of two witnesses.

JOSEPH BARRY.

WILLIAM J. THOMÉE.
